SHOCK ABSORBING MEANS FOR SHUTTLES

Robert Balfour, Dundee, Scotland

Application March 11, 1939, Serial No. 261,320

5 Claims. (Cl. 139—196)

This invention relates to shuttles and more particularly to means for reducing shock thereto and it consists in the constructions, arrangements and combination herein described and claimed.

It is an object of the invention to provide a detachable or renewable shuttle tip of a shock-absorbing type readily applicable to shuttles of various types whether for light or heavy work.

It is also an object of the invention to provide a novel means for incorporating a resilient cushion and metallic tip upon the shuttle body.

Additional objects, advantages and features of invention will be apparent from the following description considered in conjunction with the accompanying drawing, wherein

Figure 1 is a sectional view of an end of a shuttle constructed in accordance with my invention.

Figure 2 is a similar view of the invention as applied to a jute shuttle.

Figure 3 is a sectional view of a modified form shown in Figure 1.

There is illustrated a shuttle generally indicated by the reference character 10, and this may be of any usual construction whether for heavy or light weaving work.

In Figures 1 and 3 the shuttle represented is that employed in weaving light material such as woolens or linens, while in Figure 2 a construction is shown as applied to shuttles employed in weaving material such as jute, the only material difference being in the securing of the nose to the shuttle proper.

In Figure 1, the shuttle body 10 is provided with a central medial bore 11 extending longitudinally, for reception of an anchorage pin 12, which may be circumferentially recessed, as at 13, if desired.

The pin 12 is formed integrally with a plate 14, the peripheral edges of which are coincident with the contour of the shuttle, and comprises a dovetailed portion 15 for a purpose to now be described.

The portion 15 includes a plate 16, the outer edges of which are inclined to provide a positive grip within a rubber tip 17, the latter being molded or otherwise shaped to conform to the shape of the shuttle. The rubber or other resilient tip 17 has its forward end enclosed by a metallic portion 18, and in order that the tip 18 will be securely held, the tip includes inturned flanges 19 molded or embedded in the resilient material.

In Figure 3 the shuttle includes a pair of bores 11—a for reception of a like number of retainer pins 12—a on plate 14—a, the plate having inturned flanges 20 embedded in the resilient ma-

terial, the inturned flanges being in symmetry with the contour of the nose of the shuttle.

The resilient material is indicated at 17—a and the nose at 18—a, the latter comprising a stem portion 21 which is divided in opposite directions to provide an anchorage 22. The nose 18—a is indicated in this instance as a solid member.

In Figure 2 dual anchorage pins 12—b are provided integrally formed with a plate 14—b, the latter being formed with means for securing in the resilient cushion 17—b, and in the present instance, the plate 14—b will be perforated for anchorage of the resilient material. A nose 18—b is provided and in the present instance, the nose 18—b has an offset portion 23 as is required in heavy work shuttles. The nose 18—b includes inturned flanges 19—a affording securing in the resilient material 17—b.

In all forms of the device it should be understood that both ends of a shuttle will be constructed with cushioned noses, thereby eliminating noise as well as reducing shock to the loom, as well as to the shuttles proper.

It will also be seen that the noses may be readily removed from the shuttle body for replacement of new noses, since the pins 12, 12—a and 12—b are frictionally retained permitting prying of the nose from the shuttle.

While I have shown and described certain preferred forms of the device, this is by way of illustration only, and I consider as my own all such modifications in structure as fairly fall within the scope of the appended claims.

I claim:

1. A shuttle for weaving looms comprising a shuttle body, said body having a bore in its ends, a nose for the ends of the body comprising a plate, a pin on the plate frictionally engaged in the respective bores, said plate having anchorage means, a resilient member engaged with the anchorage means, and a metallic point anchored to the resilient member.

2. A shuttle for weaving looms comprising a shuttle body, said body having bores in the ends thereof, a nose for the ends of the body comprising a plate, pins on one side of the plate for frictional engagement in the respective bores, the other side of said plate having anchorage means, a resilient member engaged with the anchorage means, and a metallic point anchored to the resilient member.

3. A shuttle for weaving looms comprising a shuttle body, said body having a bore in its ends, a nose for the ends of the body comprising a

plate, a pin on the plate for frictional engagement in the bore, said plate having an integral dove-tailed member, a resilient body anchored to the dove-tailed member, a metallic point on the resilient body, said point having inturned flanges embedded in the resilient member.

4. A shuttle for weaving looms comprising a shuttle body, said body having a bore in the ends, a nose for the ends of the body comprising a plate, a pin on the plate for frictional engagement in the bore, said plate having an inturned flange, a resilient body anchored to the flange, a

metallic point on the resilient body, said point having a medially disposed stem, said stem being provided with oppositely directed arms for anchorage in the resilient member.

5. A cushioned tip for shuttles of a weaving loom comprising a metallic plate, means on one side of the plate for securement to an end of a shuttle; a nose, and a relatively thick resilient member positioned between and anchored to the nose and the other side of the plate. 10

ROBERT BALFOUR.
